(57) **CLAIM**

The ornamental design for a camera adapter, as shown and described.

DESCRIPTION

FIG. 1 is a top, front and left side perspective view of a camera adapter showing our new design; FIG. 2 is a bottom, rear and right side perspective view thereof; FIG. 3 is a bottom, front and right side perspective view thereof; FIG. 4 is a rear and left side perspective view thereof; FIG. 5 is a top plan view thereof; FIG. 6 is a bottom plan view thereof; FIG. 7 is a left side elevation view thereof, the right side elevation view being a mirror image thereof; FIG. 8 is a front elevation view thereof; and, FIG. 9 is a rear elevation view thereof. The broken lines depict portions of the camera adapter in which the design is embodied that form no part of the claimed design.

1 Claim, 9 Drawing Sheets
